US00D929396S

(12) **United States Design Patent** (10) Patent No.: **US D929,396 S**
(45) Date of Patent: **** Aug. 31, 2021**

(54) **BODY OF SMART WATCH**

(71) Applicant: **HUAWEI TECHNOLOGIES CO., LTD.**, Shenzhen (CN)

(72) Inventors: **Jianbo Zou**, Shenzhen (CN); **Juha Tapiro Kosonen**, Shenzhen (CN); **Ning Yang**, Shenzhen (CN)

(73) Assignee: **HUAWEI TECHNOLOGIES CO., LTD.**, Shenzhen (CN)

(**) Term: **15 Years**

(21) Appl. No.: **29/715,299**

(22) Filed: **Nov. 30, 2019**

(30) **Foreign Application Priority Data**

CLAIM

The ornamental design for a body of smart watch, as shown and described.

DESCRIPTION

FIG. 1 is a front view of a body of smart watch, showing our new design;

FIG. 2 is a back view thereof;

FIG. 3 is a left side thereof;

FIG. 4 is a right side thereof;

FIG. 5 is a top view thereof;

FIG. 6 is a bottom view thereof; and,

FIG. 7 is a front perspective view thereof.

The broken lines in the figures show portions of the body of smart watch that form no part of the claimed design.

1 Claim, 7 Drawing Sheets
